UNITED STATES PATENT OFFICE

KARL MAIER, OF STUTTGART, GERMANY, ASSIGNOR TO UNION SPECIAL MASCHINEN-FABRIK, G. M. B. H., OF STUTTGART, GERMANY

APPARATUS FOR FORMING BAGS

Application filed June 30, 1928, Serial No. 289,452, and in Germany December 22, 1927.

The invention relates to new and useful improvements in an apparatus for forming bags. Prior to this invention it has been customary to fold a strip about the edge portions of sections of material and to stitch the strip to the sections for reinforcing and enclosing the joined edges. The line of stitching passing through the strip into the edge portions is inserted therethrough back from the edges of the strip and this leaves the edges free so that they often become bent outwardly and torn, particularly when paper is used as the enclosing strip.

An object of the invention is to provide an apparatus for stitching a strip to sections of material for enclosing the edges thereof, which apparatus also applies an adhesive to the inner faces of the strip adjacent the edges so that the strip is not only secured to the edge portions by the stitching, but the extreme edge portions of the strip will be secured by the adhesive to the joined sections of material.

A further object of the invention is to provide an apparatus of the above type wherein the adhesive is applied to the strip or the material and distributed thereon prior to the stitching of the parts.

A further object of the invention is to provide an apparatus of the above type wherein the strip is folded about the edge portions and adhesive applied to the inner face of the strip adjacent the edges thereof as the strip is led to the stitching mechanism.

A further object of the invention is to provide an apparatus of the above type having stitching units for simultaneously stitching the opposite edge portions of sections of material for forming a bag with devices for guiding a strip to each stitching unit and for folding the same about the edge portions, and also for applying an adhesive between the edge portions of the strips and the respective sections of the material being stitched so that said strips are not only stitched simultaneously to the sections of material, but the edge portions of the strips are also secured by an adhesive to said sections of material.

These and other objects will in part be

obvious and will in part be hereinafter more fully disclosed.

In the drawings:

Fig. 1 shows more or less diagrammatically partly in section and partly in plan a portion 55 of an apparatus embodying the improvement.

Fig. 2 is an enlarged detail partly in section and partly in plan of one of the units for folding, applying an adhesive and stitching a strip to the edge portions of sections of 60 material.

Fig. 3 is a view partly in section and partly in front elevation of the parts shown in Fig. 2.

Fig. 4 is a view in side elevation of the 65 parts shown in Fig. 3.

Fig. 5 is a plan view similar to Fig. 1, but showing a modified form of apparatus.

Fig. 6 is a view somewhat similar to Fig. 2, but showing a slightly modified construction 70 of apparatus.

Fig. 7 is a view similar to Fig. 1, but showing a further modified form of apparatus.

Fig. 8 is a diagrammatic view showing the arrangement of the pipes for applying adhesive 75 after the manner disclosed in Fig. 7.

Fig. 9 is an enlarged sectional view through the sections of material with the strips attached thereto by the lines of stitching and the adhesive.

Fig. 10 is a view similar to Fig. 9, but showing a modified arrangement of the adhesive.

Fig. 11 is a view partly in section and partly in front elevation of parts of the apparatus 85 shown in Fig. 7.

Fig. 12 is a view similar to Fig. 11, but showing a modified arrangement of the parts.

The invention is directed to an apparatus for forming bags or the like from fabric, 90 paper, or any other suitable material. The apparatus preferably includes two stitching units or sewing machines, which are right and left hand units and disposed so as to simultaneously stitch the opposite edges of sections 95 of material for joining the edge portions thereof. Means is associated with each stitching unit for guiding a strip and folding a strip about the edge portions of material for enclosing the edge portions. This means 100

is located in advance of the stitching mechanism so that the line of stitching passes through the strip and secures the strip to the edge portions. Disposed in advance of the stitching mechanism are devices for applying adhesive between the inner faces of the edge portions of the strip and the material to which the strip is secured.

According to certain embodiments of the invention disclosed these devices apply the adhesive to the inner face of the strip, and according to other illustrated embodiments of the invention the devices apply the adhesive to the face of the material against which the edge portion is laid. In both instances, a distributing means is associated with each adhesive applying device so that the adhesive is properly distributed and placed for joining the edge portions of the strip to the sections of material being joined.

Referring more in detail to the drawings, the sections of material being joined are illustrated at 1. These sections are superposed one on the other. Encircling the edge portions of the sections of material at each side thereof is a strip 2. The strip is folded about the edge portions and secured thereto by a line of stitching 7. The strips are led from a suitable source of supply about guide rollers 3, and thence through a folding device 4. There is a folding device for each strip and this folding device folds the strip about the edge portions. There are two sewing units indicated at 5. These sewing units are right and left hand and are disposed so as to simultaneously form the lines of stitching 7, 7 joining the strips to the sections of material. Each sewing unit includes a needle 6 and a presser foot 18. The folders 4 are located in advance of the presser foot so that the strip is folded about the edge portions of the material and then passes beneath the presser foot so that the line of stitching passes both through the strip and the edge portions of the material.

Associated with each stitching unit and folder is a supply reservoir 8 for an adhesive material. The adhesive material may be forcibly fed from the supply reservoir by any suitable means. As illustrated, a feed screw is used which rotated by a belt wheel 10 from any suitable source of power. The adhesive material is indicated at 11. Located in the reservoir 8 is a follower 12 which may be used for loading the reservoir and for forcing the adhesive into the feed screw so that the adhesive is forcibly fed from the device. Two supply pipes 13, 13 lead from this reservoir 8 and these supply pipes are extended about the edges of the folder 4 in the embodiment of the invention illustrated in Figs. 1 to 6. The discharge nozzle for each pipe is indicated at 14. Said discharge nozzle is so positioned as to lay a strip 15 of adhesive against the inner face of the strip

2 adjacent the edge thereof. A roller 16 engages the strip of adhesive and distributes the same as indicated at 17. This distribution of the adhesive insures that the adhesive shall be properly placed relative to the extreme edge of the strip so that the adhesive will be entirely covered by the strip. The rollers 16 are carried by a supporting sleeve 19. Each roller is mounted on a shaft which is free to rotate in this sleeve bearing. The sleeve bearings 19 are mounted at the outer end of a spring bracket 20 which is secured to the folder by a bolt 21. Flexing bolts 22, 22 pass through the spring bracket and bear against the outer face of the folder. By adjusting these bolts 22, 22 the pressure of the rollers 16 against the adhesive and the inner face of the strip may be adjusted.

After the adhesive is laid against the inner face of the strip and distributed thereon, then the strip is caused to contact with the edge portions of the material being joined. This is brought about by the strip passing beneath the presser foot of the machine. It is sometimes desirable to use additional means for placing the strip against the sections being joined prior to the strip passing beneath the presser foot. In Fig. 5 of the drawings, I have shown a roller 23 mounted in suitable bearings, which roller extends across from one side of the apparatus to the other. The folders are removed from the presser feet of the sewing units a sufficient distance so as to allow this roller to engage the material prior to the material passing beneath the presser feet. The roller rolls the edge portions of the strip in firm contact with the edge portions being joined, after which they are stitched.

In Fig. 6 of the drawings, I have shown a slightly modified arrangement of means for rolling the edges of the strip into contact with the edge portions of the material being joined. In this form of the invention a roller 24 is provided which is located directly in front of the presser foot 18. Instead of having one long roller extending across the apparatus there is a separate roller associated with each presser foot. In Fig. 9 of the drawings, a sectional view is shown through the stitched sections of the material. The strip 2 is shown as folded against the edge portions of the sections being joined, the adhesive is indicated at 17 and the line of stitching at 7. Through the combined action of the line of stitching and the adhesive, the strips are secured to the opposite edges of the sections of the material encircling the edge portions thereof and firmly outside the same. Not only does the adhesive prevent the edges of the strip from turning up, but it also makes a very tight seal preventing the escape of material from the bag through the seam joining the side edge portions thereof.

In the form of the invention shown in Figs.

7 and 8 the adhesive is applied to the material itself rather than to the strip which encircles the edge. This is accomplished by pipes 25, 25. The nozzle end of each pipe is placed close to the material and lays a strip of adhesive against the upper and lower faces of the material. A roller 27 carried by a yielding bracket 29 is associated with each nozzle and this distributes the coating as indicated at 28 in Fig. 7. After the adhesive is applied to the edge portions of the material being joined the strip is laid around the edge portions and onto the adhesive and is then stitched. In Fig. 11 of the drawings the upper and lower rollers 27 for distributing the adhesive are shown in their position relative to the line of stitching which is indicated by the broken line α . Instead of having a single strip of adhesive, a plurality of strips of adhesive may be placed between the strip and the sections of material being joined as shown in Fig. 10. It will be noted that these strips of adhesive are spaced from each other and the line of stitching 7 is between the adhesive strips. This laying of the adhesive is accomplished by providing additional pipes, one for each strip. In Fig. 12 of the drawings there is shown an arrangement of distributing rollers 31, one for each of the adhesive strips which are indicated at 30. These rollers are carried by yielding bracket arms 32. The adhesive is applied by pipes as described above. When an adhesive strip is placed between the line of stitching and the extreme edges of the sections being joined, the strip is more firmly secured to the edge portions.

It is obvious that minor changes in the details of construction may be made without departing from the spirit of the invention as set forth in the appended claims.

Having fully described my invention, what I claim as new and desire to secure by Letters Patent, is:—

1. An apparatus for joining sections of material comprising a stitching unit, means for directing a strip about the edge portion of the material and to the stitching unit, and means for applying a strip of adhesive between the line of stitching and the edge of the strip, said last named means including a pipe for applying a strip of adhesive directly to the strip and a distributing roll for distributing the adhesive prior to the strip contacting with the edge portions to be joined.

2. An apparatus for joining sections of material comprising a stitching unit, means for directing a strip about the edge portion of the material and to the stitching unit, means for applying a strip of adhesive directly to the under face of the strip adjacent each edge portion thereof prior to the stitching of the strip, and rollers adapted to engage the adhesive on the strip for distributing the adhesive.

3. An apparatus for joining sections of material comprising a stitching unit, a folder for directing a strip about the edge portion of the material and to the stitching unit, and means for applying an adhesive directly to the strip adjacent each edge of the strip as it passes through the folder and prior to the stitching of the strip.

4. An apparatus for joining sections of material comprising a stitching unit, a folder for directing a strip about the edge portion of the material and to the stitching unit, means for applying an adhesive directly to the strip adjacent each edge of the strip as it passes through the folder and prior to the stitching of the strip, and a roller adapted to engage the material to which the adhesive is applied for distributing the adhesive.

5. An apparatus for joining sections of material comprising spaced stitching units for simultaneously stitching the opposite edge portions of the material, means associated with each stitching unit for directing the strip about the edge portion of the material to the stitching unit, and means associated with each stitching unit for applying the strip of adhesive between the line of stitching and the edge of the strip, said last named means including pipes, means for supplying said pipes with adhesive under pressure, each pipe having a nozzle for applying a strip of adhesive directly to the strip and a roller associated with the nozzle for distributing the adhesive.

6. An apparatus for joining sections of material comprising spaced stitching units for simultaneously stitching the opposite edge portions of the material, a folder associated with each stitching unit for directing a strip about an edge portion of the material and to the stitching unit, and means for applying an adhesive directly to the strip adjacent each edge of the strip as it passes through the folder and prior to the stitching of the strip.

7. An apparatus for joining sections of material comprising spaced stitching units for simultaneously stitching the opposite edge portions of the material, a folder associated with each stitching unit for directing a strip about an edge portion of the material and to the stitching unit, means for applying an adhesive directly to the strip adjacent each edge of the strip as it passes through the folder and prior to the stitching of the strip, and a distributing roll for distributing a strip of adhesive.

8. An apparatus for joining sections of material comprising spaced stitching units for simultaneously stitching the opposite edge portions of the material, a folder associated with each stitching unit for folding a strip about the edge portion of the material and directing the same to the stitching unit, an adhesive supply pipe extending about each

edge of the folder and disposed so as to apply adhesive to the inner face of the strip adjacent the edge thereof, a yielding bracket attached to the folder, a roller mounted at each end of said bracket and engaging the inner face of said strip between the adhesive supply pipe and the stitching mechanism for distributing the adhesive.

9. An apparatus for joining sections of material comprising spaced stitching units for simultaneously stitching the opposite edge portions of the material, a folder associated with each stitching unit for folding a strip about the edge portion of the material and directing the same to the stitching unit, an adhesive supply pipe extending about each edge of the folder and disposed so as to apply adhesive to the inner face of the strip adjacent the edge thereof, a yielding bracket attached to the folder, a roller mounted at each end of said bracket and engaging the inner face of said strip between the adhesive supply pipe and the stitching mechanism for distributing the adhesive, and a roller located between the folder and the stitching unit for placing the strip against the material.

In testimony whereof, I affix my signature.
KARL MAIER.
